ARTIFICIAL TOOTH

Leopold Egger, Linz, Upper Austria

Application August 7, 1947, Serial No. 766,997
In Austria July 7, 1946

Section 1, Public Law 690, August 8, 1946

10 Claims. (Cl. 32—8)

1

This invention relates to artificial teeth as may be used for whole or partial dental plates as well as for bridge work.

It is an object of this invention to provide an artificial tooth whose crown is capable of yielding to chewing pressure to substantially the same limited extent as do the natural teeth.

A further object of the invention is to provide a composite artificial tooth whose elements are constructed and associated in such a manner as to permit a limited swinging movement of the crown of the tooth relative to the base of the denture without rendering by such construction the appearance of the tooth noticeably different from that of ordinary artificial teeth.

A further object of the invention is to provide an artificial tooth which combines limited relative movability of its crown with sufficient strength to take up any chewing pressure.

Still a further object of the invention is to provide a composite artificial tooth having a crown whose active rim or surface may swing for relatively wide amounts due to a deeply located pivot for said crown.

Other objects of the invention will appear as the description proceeds, reference being had to the accompanying drawing which illustrates by way of example three embodiments of the invention and in which—

Fig. 1 is a vertical section through an anterior tooth as secured to a base plate;

Fig. 2 is a section along the line 2—2 of Fig. 1;

Figs. 3 and 4 are, respectively, vertical sectional views of the crown of a molar tooth and of the coordinated portion of a base member; and

Fig. 5 shows a vertical section through a modified form of an anterior tooth and base plate.

The tooth shown in Figs. 1 and 2 consists of three parts, namely, a support or carrier portion 10, a crown 11, and an intermediate layer 12. These three parts may all be made of synthetic material, the support 10 and the crown 11 of non-elastic synthetic material, such as plastic resins, and the intermediate layer 12 of elastic synthetic material, such as synthetic elastomers. If consisting of such synthetic plastics, the parts 10, 11 and 12 may be polymerized together to form a unitary body of uniform appearance and the tooth may, through the intermediary of its part 10, be bonded or fused to the conventional base plate 13 of the denture also by the polymerization method, if this plate also consists of polymerizable material, e. g. an acrylic resin.

The support 10 is in the form of a substantially conical pin which is rounded off at its apex to

2

form a rolling surface 14 and is provided at its base with a marginal flange 15. The crown 11 has at its lower side a conical cavity 16 whose apex is shaped into a rolling surface 17 adapted to cooperate with the rolling surface 14 of the pin 10.

The slopes of the conical surfaces of the pin 10 and the cavity 16 are so chosen that, when the axes of these two conical surfaces coincide, which position is shown in Fig. 1, an annular gap is present between the pin 10 and the crown 11 which accommodates the intermediate layer 12 and whose width increases steadily from the rolling surfaces 14, 17 towards the mouth of the gap at the lateral surface of the tooth. While the annular gap does not have to have the exact form shown in Fig. 1, it is essential that its shape is such as to permit the crown 11 which bears with its rolling surface 17 directly, that is without an intervening elastic cushion, upon the rolling surface 14, to carry out a pendulous movement in all directions during chewing. Under this condition the crown 11 can react to the chewing pressures in the same manner as would a natural tooth.

While the linear extent of the swing of the crown edge may be varied by lengthening or shortening this crown edge, the tooth will in any case be able during the chewing action to slightly give way to the food seized by the teeth, and to adapt itself to natural articulation. The similarity to natural teeth becomes practically perfect if the palatal surface, in particular that of the front teeth, is shaped so as to exactly correspond to the shape of the palatal surface of the natural teeth.

In the conventional artificial teeth this surface is either shortened or arbitrarily modified. It being, however, the task of just the front teeth to cut up the food, the heretofore inadequate function of these artificial front teeth is the main cause of the unpleasant vexations with which the wearer of an artificial denture has often to put up in chewing.

In the modified form of the tooth shown in Figs. 3 and 4 there are only two parts, the crown 18 and the intermediate layer 21, which have to be formed separately from the base plate 22. While there is again a conical support 23 corresponding to the pin 10 of Fig. 1, this support or pin is an integral part of the base plate 22, and the pins for all the teeth carried by the base plate may be formed with the latter in the same molding operation. The crown 18 of non-elastic synthetic material has again a conical cavity 19 whose bottom is shaped so as to form a bearing cup having a rolling surface 20. The cavity 19, except for

the rolling surface 20, is lined with a layer 21 of elastic synthetic material whose cross-section, starting from the bearing cup 20, increases uniformly. At its lower end the layer 21 is shaped into an annular flange 24 whose upper surface 25 rests against the bottom surface 26 of the crown 18 and whose lower surface 27 corresponds in shape approximately to the surface 28 of the base plate 22 so that, when the crown together with its lining is placed upon the support 23, the surface 28 of the base plate 22 affords a suitable seat for the surface 27 of the lining.

The plate 22 which is made of non-elastic synthetic material is shaped so as to present a support in the form of a conical pin 23 for each tooth of the set of teeth to be carried by the plate. After the tooth shown in Fig. 3 has been placed on its coordinated pin shown in Fig. 4, a permanent connection between the tooth and the base member 22, 23 is brought about by a suitable bonding method, such as by polymerizing.

The break in the profile of the annular gap shown in Fig. 1 at 40 as well as in Fig. 3 at 41 providing surfaces of small slope at the wide end of said gap improves the seat of the crown on the pin.

Fig. 5 shows a modification of the new tooth permitting for the same distance of the tip of the tooth from the base plate a wider swing of said tip than the constructional forms shown in Figs. 1 to 4. In the latter, the bearing point of the crown on the support or pin is situated at about one-half of the total height of the tooth which arrangement is ordinarily sufficient to allow for pendulous movements of proper extent of the chewing rim or surface of the tooth. The chewing rim or surface can swing out the wider, the deeper the bearing point of the crown is located. Lowering this bearing point reduces the height of the supporting pin, but it also reduces the height of the elastic intermediate layer. It is not desirable to reduce this elastic layer below a certain height. In order to permit a lower location of the bearing point of the crown on its support without reduction of the elastic intermediate layer, I have devised the tooth shown in Fig. 5. This tooth is composed of a support 30 which forms a bearing cup 31 open towards the top, a crown 32 whose lower half is in the form of a conical pin 33, and an intermediate layer 34. The apex of the conical pin 33 is rounded off so as to form a rolling surface 35 which cooperates with a rolling surface 36 formed at the bottom of the bearing cup 31. The annular gap between the support 30 and the pin portion 33 of the crown 32 which is occupied by the intermediate layer 34 increases in width uniformly towards its mouth. Due to this reversed arrangement of pin and bearing cup, as compared with the arrangements shown in Figs. 1 to 4, the bearing point of the crown becomes situated much lower so that any desired maximum amplitude of the swing of the crown may be provided for by proper dimensioning of the cushion 34.

The invention proves of particular advantage when applied to molar teeth since with these teeth it is especially important that they can yieldingly adjust themselves to such natural teeth as the wearer of the denture may still possess.

The swing bearing of the crown prevents, particularly if the palatal surface of the artificial teeth conforms exactly with that of the natural teeth, any displacement of the denture and allows for a completely natural chewing action so

that the denture satisfies all demands which may be made upon a biotechnically perfect denture.

While I have mentioned synthetic materials for the various parts of the new teeth, I desire it to be understood that also other materials may be used, such as metal or porcelain for the support and the crown and rubber for the elastic intermediate layer. The resiliency of this intermediate layer preferably corresponds approximately to that of rubber for erasers.

What I claim is:

1. A composite artificial tooth comprising a supporting member, a crown, an elastic layer interposed between said supporting member and said crown, a rolling surface on said supporting member and said crown being shaped so that one of said two parts comprises a pin and the other a bearing cup which pin and bearing cup interact at said rolling surfaces, and said supporting member and crown forming between themselves an annular gap occupied by said elastic layer.

15 2. A composite artificial tooth as claimed in claim 1, wherein said pin is part of said supporting member and said bearing cup is part of said crown.

25 3. A composite artificial tooth as claimed in claim 1, wherein said pin is part of said crown and said bearing cup part of said supporting member.

30 4. A composite artificial tooth comprising a supporting member, a crown, an elastic layer interposed between said supporting member and said crown, a rolling surface on said supporting member, a rolling surface on said crown, said supporting member and said crown being shaped so that one of said two parts comprises a pin and the other a bearing cup which pin and bearing cup interact at said rolling surfaces, said pin and said bearing cup having each substantially conical shape with the slopes of the two conical surfaces being different so as to form between them an annular, towards the side wall of the tooth substantially steadily widening, gap occupied by said elastic layer.

45 5. A composite artificial tooth as claimed in claim 4, wherein the end portion of said annular gap at the wide side thereof is or reduced slope as compared with the rest of said gap.

50 6. A denture comprising a base plate and at least one composite artificial tooth, said base plate having integral therewith a pin-shaped extension for each artificial tooth carried by said plate, a rolling surface on each said pin-shaped extension, each tooth consisting of a crown having a cavity and an elastic layer fitting into said cavity, a rolling surface delimiting a portion of said cavity adapted to cooperate with said rolling surface on the coordinated pin-shaped extension of said base plate, said elastic layer fitting into said cavity and onto said pin-shaped extension to the exclusion of said rolling surface of said cavity and said extension.

65 7. As an article of manufacture an artificial tooth unit consisting of a crown having a substantially conical cavity whose apex is rounded off, and an elastic layer lining the conical wall of said cavity with the exception of said rounded off part at the apex of said conical wall.

8. As an article of manufacture an artificial tooth unit consisting of a non-elastic crown having a substantially conical cavity whose apex is rounded off, and an elastic layer lining the conical wall of said cavity with the exception of said

rounded off part at the apex of said conical wall, the thickness of said layer increasing towards the open end of said cavity.

9. A composite artificial tooth comprising a supporting member and a crown consisting of non-elastic polymerizable synthetic material and an intermediate layer of elastic polymerizable synthetic material interposed between said supporting member and said crown, a rolling surface on said supporting member, a rolling surface on said crown, said supporting member and said crown being shaped so that one of said two parts comprises a pin and the other a bearing cup which pin and bearing cup interact at said rolling surfaces, said supporting member and crown forming between themselves an annular gap occupied by said elastic layer, and said supporting member, crown, and intermediate layer being polymerized together.

10. A denture comprising a base plate of polymerizable synthetic material and at least one composite artificial tooth comprising a supporting member and a crown, both consisting of non-elastic polymerizable synthetic material, and a

5

10

15

layer of elastic polymerizable synthetic material interposed between said supporting member and said crown, a rolling surface on said supporting member, a rolling surface on said crown, said carrier and said crown being shaped so that one of said two parts forms a pin and the other a bearing cup which pin and bearing cup interact at said rolling surfaces, said supporting member and crown forming between themselves an annular gap which is occupied by said elastic layer, said supporting member, crown, and intermediate layer being polymerized together, and said supporting member being polymerized to said base plate.
